CLAIM

The ornamental design for a travel case for battery operated toothbrush, as shown and described.

DESCRIPTION

FIG. 1 is a perspective view of a first embodiment of a travel case for battery operated toothbrush in closed position;

FIG. 2 is a top view thereof;

FIG. 3 is a front view thereof;

FIG. 4 is a bottom view thereof;

FIG. 5 is a rear view thereof;

FIG. 6 is a left side view thereof; and

FIG. 7 is a right side view thereof.

FIGS. 8-10 are perspective views of a second embodiment of a travel case for battery operated toothbrush in open position;

FIG. 11 is a top view thereof;

FIG. 12 is a front view thereof;

FIG. 13 is a bottom view thereof;

FIG. 14 is a rear view thereof;

FIG. 15 is a right side view thereof; and,

FIG. 16 is a left side view thereof.

Broken lines are used in the drawings to designate parts of a travel case for battery operated toothbrush that form no part of the claim.
